UNITED STATES PATENT OFFICE.

GEORGES CLOETENS, OF BRUSSELS, BELGIUM.

REED-ORGAN.

1,179,504.

Specification of Letters Patent. Patented Apr. 18, 1916.

Application filed March 20, 1911. Serial No. 615,767.

To all whom it may concern:

Be it known that I, GEORGES CLOETENS, a subject of the Kingdom of Belgium, residing at 37 Rue de Eausanne, Brussels, in Belgium, have invented certain new and useful Improvements in Reed-Organs; and I do hereby declare the following to be a full, clear, and exact description of the invention, such as will enable others skilled in the art to which it appertains to make and use the same, reference being had to the accompanying drawings, and to letters or figures of reference marked therein, which form a part of this specification.

The present invention relates to improvements in reed organs with beating reeds, and more particularly to improvements in reed organs with beating reeds of the kind described in my prior United States Patent No. 1,095,268, dated May 5, 1914.

The purpose of this invention is to improve upon the organ of the aforesaid patent in order to increase its commercial and musical value.

In accordance with one feature of the present invention, I provide an organ comprising a resonating pipe, a plurality of beating reeds of different pitch forming a scale, an air chest in communication with said reeds, and valves between said reeds and said resonating pipe controlling the selection of said reeds.

In accordance with another feature of my invention, I provide an organ comprising a resonating pipe, a plurality of beating reeds of different pitch forming a scale, means for supporting said reed and valves for said reeds adjacent said reed-supporting means for controlling the selection of said reeds.

These and further features of the invention will now be described and claimed.

Some preferred forms of my invention are illustrated in the accompanying drawing, in which:—

Figure 1 is an axial section through the resonating pipe and reed chest of an organ embodying the invention. Fig. 2 is a vertical section on the line 2—2 of Fig. 1. Fig. 3 is a view similar to Fig. 1 of another embodiment of the invention, this form of organ being somewhat like that shown in my aforesaid prior patent. Fig. 4 is a vertical section through the construction of Fig. 3. Fig. 5 shows a detail.

The simple and relatively inexpensive

type of organ stop shown in Figs. 1 and 2 has an air chest 43 connected with an auxiliary or distributing air chest 44 by means of axially-disposed air-distributing openings 44^a each controlled by a valve 58 normally held seated by a spring 46, and operable by valve-rods 48 which are operably connected in well known manner (not shown) with the usual stop-action of the instrument, in order to connect said air chests and regulate the distribution of the air supply in the compartments, hereinafter described, of the chest 43. The tube 47 connects the distributing chest with a well known wind apparatus, not illustrated. A partition 49, shown in dotted lines in Fig. 1, in the air chest 43, and separating the distributing openings 44^a (or a plurality of such partitions, if there be more than two distributing valved openings) divides the air chest 43 into a plurality of compartments 43^a, 43^b, etc., each having an independent connection with the air distributing chest 44 and each connected with or containing a note-sequence. This organization replaces and is an improvement upon the usual stop-slide arrangement because if all the valves 58 be simultaneously operated, they perform the same function as the stop-slide, while by operating said valves separately, separate sequences in the note-series may be controlled in any desirable manner.

The resonator 16, is mounted axially on the air chest 43, and is conical, its cross section being substantially a quadrant sector, as shown in Figs. 2 and 4; one of its plane walls coincides with and may be the top or sounding board 45 of the air chest 43, and its standing wall 28 may be removable to facilitate assembling and repairs; its small end is preferably but not necessarily open and its large end may terminate in a suitable bell 17, as illustrated in Fig. 1; or, as in Fig. 5, may be adapted to connect with a tonal slide 30. An auxiliary tube 24 is mounted on the resonating pipe and connected with it centrally and at its ends.

A series of tongues 18, each suitably mounted on a reed tube 19, attached to the board 45 and communicating with the resonating pipe by an air port 36^a, extend into the air box 43. The longer reeds which sound the lower notes are connected with the smaller part of the resonating pipe and extend into the air chest compartment 43^b, and the shorter reeds which sound the

higher notes, are connected with the larger part of the resonating pipe and extend into the air chest compartment 43^a, so that the high and low note-sequences can be controlled, jointly or independently, by the valves 58.

The air ports 36^a are each controlled by a note-valve 36 which lifts into the resonating pipe and is operably connected with a key action (not illustrated) of the instrument by a valve-rod or wire 42, which is suitably guided by passing through openings in a guide frame 40 and in reinforcing plates 51 fixed on the horn 16. The guide frame 40 may be attached to a wall of the air-chest 43 by standards 41. The note-valves 36 may be seated by gravity and to that end heavy washers or weights 37 may be fixed to the wires 42; or by the elasticity 20 of springs 39 strained between the frame 40 and washers 38 on the wires 42.

A wire 50 extends through a hole in the board 45, to each air port 36^a and can be advanced into or withdrawn therefrom to regulate the air supply by varying the size and shape of the port. Connected with each tongue 18 is a tuning wire 29 which comprises a head in contact with and slideable upon the tongue to lengthen or shorten 30 its vibrating end and a wire which extends through the board 45 adjacent the standing wall 28 of the resonating pipe.

The operation of this type of organ stop is as follows: The player strikes keys operably connected with drivers of the note valves 36 and raises them; air passes through reeds 19 and causes tongues 18 to vibrate and sound musical notes which are amplified by the vibrations of the walls of the 40 resonating pipe 16 and of the auxiliary pipe 24, said notes being modified by the form of the particular pipe extension or bell of the tonal slide 30 then in register with the resonating pipe. The player can 45 shift the tonal slide, bring its several "bells" successively into register with the pipe and thereby modify the expression and effect; and by suitably manipulating the stop action he can operate the valves 58 either 50 simultaneously or independently and control the volume of all the notes of the series or of note-sequences thereof, in a manner much superior to what is possible with the usual stop-slides. This type of instrument can 55 be operated by "wind" or air at positive pressure admitted by the pipe 47; but with reeds mounted in the proper manner the instrument will give the purest notes if operated by suction.

60 Figs. 3 and 4 illustrate the application of my improvements to a stop generally like that of my aforesaid patent in that each tongue 18 and its reed is in a separate cell, 56, of the air chest 43, the stop slides are 65 of the usual kind and the note valves 36

are exterior to the stop-slide and are located in an air passage 21, which communicates with the air pipe 47; but unlike it in that each reed-cell 56 communicates freely with the pipe 16 by an opening 53 and each reed tube 19 is attached to and envelops a port in the bottom of the air chest 43. The above described improvements with the reeds mounted in the usual manner, enable me to produce the purest 75 notes by air under pressure. The conduit 47 leading from the chamber 21 is connected with a well known suction apparatus, not illustrated.

Fig. 5 illustrates an improved mode of 80 using a tonal slide 30 bearing a plurality of different bells, such as described in my aforesaid patent.

Adjacent to the large end of each resonating pipe 16, I provide a valve 72 preferably 85 interior to the tonal slide, hinged to swing inwardly, and provided with two independent means of operation, viz., a valve stem 72^a fixed to the valve, and a rocker-and-link connection comprising a bell-crank 74 and 90 flexible link or cord, 74^a connecting the bell-crank and valve. The stem 72^a can be suitably connected to be operable from one source and the bell crank suitably connected to be operable from another source 95 and because of the flexible link connection, the valve can be operated from either source independently of the other.

In the aforesaid prior patent the note valves and reeds connect with opposite ends 100 of the reed cells, while in this said valves are one, or as closely adjacent as possible to, that end of the reed cells to which the reeds are connected. In the older construction the opening of a note valve 36 causes, first, 105 motion of the entire body of air in the connected reed cell; and second, the vibration of the reed and the production of sound; while in the improved construction this sequence is secured and (with the modes of air 110 movement best adapted to the several constructions illustrated) the note is sounded first and the air in the air cell moved second. It is obvious that the present invention shortens the elapsed time between the striking 115 of a key and the sounding of the corresponding note, makes the instrument more sensitive and responsive to the feelings of the player and enables him to easily attain expression difficult with the older instrument. 120

It will be understood that the drawings illustrate one stop or bank of an organ and that a plurality of similar stops having varying tone-qualities may be combined in an organ, as is characteristic of that instrument.

What I claim is:—

1. A reed organ comprising a resonating pipe, a plurality of beating reeds of different pitch forming a scale, an air chest in 125

communication with said reeds, and valves between said reeds and said resonating pipe controlling the selection of said reeds.

2. A reed organ comprising a resonating pipe, a plurality of beating reeds of different pitch forming a scale, a plurality of chambers constituting an air chest in communication with said reeds, valves between said reeds and said pipe controlling the selection of said reeds, and means for controlling the air pressure in said chambers.

3. A reed organ comprising a resonating pipe, a plurality of beating reeds of different pitch communicating with said pipe, selective means for controlling said reeds, a slide arranged to move across the mouth of said pipe, a plurality of "bells" carried by the slide to be brought selectively into registry with said pipe, and a valve between said pipe and said slide.

4. A reed organ comprising a resonating pipe, a plurality of beating reeds, an air chest in communication with said reeds, valves between said reeds and said resonating pipe controlling the selection of said reeds, and means associated with said pipe to vary the quality of sound produced.

5. A reed organ comprising a resonating pipe, a plurality of beating reeds, an air chest in communication with said reeds, valves between said reeds and said resonating pipe controlling the selection of said reeds, and means for varying the resonant effect of said pipe.

35 6. A reed organ comprising a resonating pipe, a plurality of beating reeds, an air chest in communication with said reeds, valves between said reeds and said resonating pipe controlling the selection of said reeds, a slide arranged to move across one end of said pipe, and a plurality of "bells" carried by the slide to be brought into registry with said pipe.

40 7. A reed organ comprising a resonating pipe, a plurality of beating reeds, an air chest in communication with said reeds, valves between said reeds and said resonating pipe controlling the selection of said reeds, and a chamber opening into said pipe 50 and forming an auxiliary passage from one part of said pipe to another part thereof.

55 8. A reed organ comprising a resonating

pipe, beating reeds of different length communicating with said pipe with the longer reeds and shorter reeds arranged respectively at the narrower and wider parts of said resonating pipe, an air chest communicating with said reeds, and valves between said reeds and said pipe.

9. A reed organ comprising a resonating pipe, a plurality of beating reeds, a plurality of chambers constituting an air chest in communication with said reeds, valves between said reeds and said pipe, and valves controlling said air chest.

10. A reed organ comprising a resonating pipe, a plurality of beating reeds of different pitch forming a scale, means for supporting said reeds, and valves for said reeds adjacent said reed-supporting means for controlling the selection of said reeds.

11. A reed organ comprising a resonating pipe, a plurality of beating reeds of different pitch forming a scale, a support for said reeds, and valves for said reeds mounted on said support, said valves controlling the selection of said reeds.

12. A reed organ comprising a resonating pipe, a plurality of beating reeds, a support for said reeds, valves on said support for controlling the selection of said reeds, a plurality of chambers constituting an air chest in communication with said reeds, and means for controlling said air chest.

13. A reed organ comprising a plurality of beating reeds, a resonating pipe, and a valve controlling the outlet to said pipe.

14. A reed organ comprising a plurality of beating reeds, a resonating pipe, a plurality of "bells" movable across the mouth of said pipe and an independently operable valve in the mouth of said pipe.

15. A reed organ comprising a plurality of beating reeds including reed tubes, a resonating pipe, and valves for said beating reeds contiguous to the open ends of said tubes for selectively controlling said reeds.

In testimony that I claim the foregoing as my invention, I have signed my name in presence of two subscribing witnesses.

GEORGES CLOETENS.
